UNITED STATES PATENT OFFICE.

FRANK GRAY, OF PHILADELPHIA, PENNSYLVANIA.

DAMPER-REGULATOR.

1,398,895.

Specification of Letters Patent.

Patented Nov. 29, 1921.

Application filed October 11, 1919. Serial No. 329,923.

To all whom it may concern:

Be it known that I, FRANK GRAY, a citizen of the United States, residing at Philadelphia, in the county of Philadelphia and 5 State of Pennsylvania, have invented new and useful Improvements in Damper-Regulators, of which the following is a specification.

This invention relates to stoves and 10 furnaces, particularly to damper control means, and has for its object the provision of a fluid pressure operated device including differential pistons connected with a damper control lever, the lever being weighted 15 whereby the damper will not be moved until steam pressure exceeds a certain predetermined amount.

An important object is the provision of a 20 device of this character which will be simple and inexpensive in manufacture and installation, which will be entirely automatic in operation, efficient and durable in service, and a general improvement in the art.

With the above and other objects and advantages in view, the invention consists in the details of construction to be hereinafter more fully described and claimed, and illustrated in the accompanying drawings in which—

30 Figure 1 is a longitudinal sectional view of my device,

Fig. 2 is a central vertical cross sectional view.

Fig. 3 is a horizontal sectional view taken 35 on the line 3—3 of Fig. 2.

Fig. 4 is a side elevation of a furnace showing my device associated therewith.

Referring more particularly to the drawings, the numeral 10 designates a casing 40 which may conveniently be formed as a single casing formed in its lower portion with a reservoir space 11 within which is disposed oil, and formed in its upper portion with a pair of cylinders 12 and 13, of 45 somewhat different diameters, 13 being the smaller. The central portion of the casing above the reservoir space 11 is provided with a passage 14 into which leads the steam pipe from the boiler of a furnace whose damper 50 is to be regulated. Formed upon the top of the casing 10 is an extension 15 upon which is pivoted, as shown at 16, a lever 17 which is connected with the damper to be controlled and which carries an adjusting 55 weight 18.

Slidable within the cylinders 12 and 13

are pistons 19 and 20, respectively, which are provided with rods 21 pivotally connected with the lever 17.

In the operation of the device, steam from 60 the boiler of the furnace to be regulated will enter the passage 14 and will place the oil within the reservoir 11 under pressure, forcing the oil upwardly into the cylinders 12 and 13. Owing to the difference in diameter 65 and consequently the area of the pistons, there will be different pressures exerted upon them in proportion to the area so that there is ordinarily a tendency to move one piston upwardly farther than the other one. 70 This tendency is counter-acted by the adjustable weight 18 which may be slid along the lever 17 to such position that the position of the lever 17, and consequently the damper, will not be changed until the steam 75 pressure entering the passage 14, exceeds a certain predetermined degree. When such excessive pressure occurs sufficient to overcome the balancing effect of the weight 18, the lever 17 will be moved and the damper 80 will be closed.

From the foregoing description and a study of the drawings it will be apparent that I have thus provided a simple and inexpensive automatic damper control device 85 which is operated entirely by steam pressure within the boiler of the furnace to be regulated, and it will be apparent that adjustment may be made to vary the susceptibility of the device within a wide range, in an 90 extremely simple and efficient manner.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. In combination with a furnace and its boiler, the furnace being provided with a damper, a regulator comprising a casing containing a liquid adapted to be placed under pressure by steam generated within the 105 boiler of the furnace, a pair of pistons disposed within said casing and arranged to be acted upon by the liquid therein under pressure, said pistons being of different diameters, and a lever connected with the damper 110 and connected with said pistons at opposite sides of its fulcrum.

2. In combination with a furnace having a boiler and a damper, a regulating device comprising a casing having its lower portion formed as a liquid reservoir, said casing being provided with a steam passage communicating with said reservoir and connected with the boiler of the furnace, a pair of cylinders of different diameters formed in

said casing and communicating with said reservoir, a lever connected with the damper 10 and pivoted upon said casing, pistons disposed within said cylinders and connected with said lever at opposite sides of its fulcrum, and a weight slidable upon said lever.

In testimony whereof I affix my signature. 15

FRANK GRAY.
